UNITED STATES PATENT OFFICE.

CHARLES TURNER BROWN, OF CHICAGO, ILLINOIS, ASSIGNOR OF SIXTY-SIX AND TWO-THIRDS ONE-HUNDREDTHS TO JOHN H. WARE, OF CHICAGO, ILLINOIS.

SHOCK-ABSORBER.

1,161,185.

Specification of Letters Patent. Patented Nov. 23, 1915.

Substitute for application Serial No. 726,916, filed October 31, 1912. This application filed March 13, 1913. Serial No. 753,897.

To all whom it may concern:

Be it known that I, CHARLES TURNER BROWN, a citizen of the United States, and a resident of Chicago, in the county of Cook and State of Illinois, have invented certain new and useful Improvements in Shock-Absorbers or Shock-Precluders for Spring-Vehicles, of which the following is a specification.

10 This invention relates to devices which are interposed between the axles of a spring equipped vehicle and the body thereof, (or chassis), with the design of lessening the shock or blow resulting from striking an obstruction, or running into a hole or rut in the road.

The objects of this invention are: to obtain a device which will prevent the breaking of springs when an obstruction or a hole is encountered while the vehicle is moving at a considerable rate of speed, either by the direct action of the springs or by the recoil of the springs from the initial compression thereof; to obtain a device which will not lessen the resiliency of the springs during the ordinary operation thereof; to obtain a device which will obviate the necessity of binding the leaves of the spring together to prevent breaking thereof; to obtain a device which will permit a spring of greater resiliency to be used in a vehicle of a given weight without danger of breaking the same than could otherwise be used; to obtain a device which is not affected by water, mud, dirt, or even damp air, when in use; to obtain a device which is durable and not easily got out of repair or broken; to obtain a device which is easily attached to vehicles, particularly to automobiles, of different designs and sizes; and to obtain a device which can be attached to the right or left hand side of the vehicle, as a right or left hand device.

An additional and particular object is to obtain a device not requiring frequent or skilled care and attention after it has once been properly installed, and a device which can be examined and the parts thereof which are most likely to become worn can be replaced without removing the device from its position on the vehicle.

In the drawings accompanying and forming a part hereof Figure 1 is a top plan view of a device embodying the invention. Fig. 2 is a vertical section on line 2-2 of Fig. 1,

viewed in the direction indicated by the arrows. Fig. 3 is an end elevation, showing the leaves of the spring of a vehicle in section and a portion of the axle in elevation. Fig. 4 is a top plan view of the movable parts of the device removed from the cylinder in which said parts reciprocate. Fig. 5 is a side elevation of one of duplicate parts which form elements of the valve operating mechanism of the device. Fig. 6 is an end elevation of said elements of the valve operating mechanism. Fig. 7 is a vertical section of one end of a compression piston removed from the piston stem of the device, and Fig. 8 is an end elevation of the elements illustrated in Fig. 7.

A reference character applied to designate a given part indicates said part throughout the several figures of the drawing wherever said character appears.

A is a shell or casing, and comprises the middle part *a*, cylinder *a'* and ends *a''* to said cylinder.

a''' is packing which is interposed between the ends of the cylinder *a'* and ends *a''*.

B is a slot in cylinder *a'*, through which slot a lever, hereinafter described, is inserted.

b, *b*, are rivets to maintain cylinder *a'* in place in middle part *a*. Part *a* of the shell is provided with an oil duct, and C is a small bolt or screw closing said duct. When said bolt is removed from said duct the interior of the shell or casing is in communication with the atmosphere; but the operation of the device is not affected thereby, except that, when said duct is open oil may be forced therethrough, and dirt, or water, or both, may to a limited extent also find way through said duct.

D is a journal bearing on the middle portion (*a*) of shell A.

E is a shaft journaled in bearing D, and *e* is a lever which is integral with said shaft. Bearing D therefore constitutes the fulcrum of said lever *e*.

F is an arm which is secured on the end of shaft D and keyed thereto to turn therewith.

f are keys which respectively fit in keyways provided therefor in shaft E and in the hub of said arm F.

F is a nut on shaft E, holding arm F firmly in place.

G is a link which is attached at one end to one end of the arm F and at the other end to the chassis X.

H is the stem of the pistons of the device and I are the pistons.

h is an aperture in stem H, and h' are rollers which are rotatably mounted on pins or axles h'' in said aperture.

When stem H and pistons I are mounted 10 in cylinder a' lever e is in aperture h and between rollers h', and the turning of said lever on its fulcrum moves said pistons and stem longitudinally in said cylinder. Stem H is provided with apertures H' which extend through disks H''. Disks H'' are integral with stem H and constitute a part of the pistons I. Pistons I respectively consist, (in addition to the disks H'') of the cups i, disks J and valves K. Disks J are 15 provided with stems or hubs j which fit in apertures in disks H''. Stems j are provided with apertures therethrough and valves K are mounted in said passage ways.

L are screws adapted to hold disks J and 20 cups i in place on disks H''. Valves K are provided with disks k, seating on seats k' to close the passage way k''' through said valve.

k'' is a spring, yieldingly holding disk k 25 to its seat.

The mechanism which controls the opening of valves K comprises duplicate heads l joined by bar l', connections M and springs N. These parts constitute what I term an 30 additional piston O. Heads l are provided with circular recesses or wells m, and connections M are illustrated as tubes fitting in said recesses or wells. Springs N are contained in tubes M and the ends of said 35 springs abut against the bottoms of wells m, thereby forcing heads l out against the cylindrical wall of cylinder a'. Said heads are forced against said walls to produce sufficient friction between them to hold said 40 additional piston O stationary while piston stem H and pistons I are moved to force the end of the stem of the valve which is in the rear piston against connection M, thereby moving the disk of said valve off from its 45 seat. The movement of the piston stem and pistons I to force the valve stem of the valve in the rear piston against the connection M in the rear one of the additional pistons moves the forward one of the pistons I to 50 carry the stem of the valve contained in said forward piston away from the connection M in the forward one of the additional pistons, and the spring k'' of said valve seats the disk thereof, to close said forward valve. 55 When a disk k is unseated the chamber in cylinder a' which is between the piston which is provided with said disk and the end of the cylinder is in communication with the chamber between the pistons, and when 60 a disk k is seated the chamber between the

piston which is provided with said seated disk and the end of the cylinder a' is air tight, that is, is not in communication with said chamber between the pistons.

Shell A is provided with web P, by 70 means of which the device is readily attached to a vehicle by placing said web underneath the U-shaped clips Y which holds leaves Z of the springs of the vehicle to the axle. 75

Q are adjusting screws in disks H'', by means of which the movements of pistons I, while additional pistons L remain stationary on the change of direction of movement of pistons I, are determined. It will be observed that the movement which is permitted by the adjusting screws Q, during the time that the additional pistons O remain stationary, is sufficient to force the disk k of valve K which is in the rear piston I, (in whichever direction said pistons are moving), off its seat, by coming against the end of the stem of said disk, and also, is sufficient to move the connection M adjacent to the end of the stem of the disk k of the valve which is in the forward piston I away from said stem, to permit the spring k'' to seat the said disk. It occurs, therefore, that when said pistons I are moving in either direction air is being compressed 85 in the chamber in front of the forward piston, and air is flowing from the middle chamber, (from between pistons I) into the chamber to the rear of the rear piston; and when a change of movement of said pistons I is effected by the recoil of the springs of the vehicle the closed valve is immediately opened releasing the air which is under pressure, and the open valve is immediately closed so that the return movement of the 90 said pistons I will put it under pressure. A greater quantity of air at atmospheric pressure is, of course, contained in the chamber in which the air is compressed by what I have just termed the return movement than 95 is first put under pressure.

To render the device a right and left hand device I put two keyways in shaft E and in the hub of arm F, and shape the end of lever e so that either end of shaft E may be at a given end of the bearing D. Cylinder a' being provided with the rectangular slot B is considered, so far as its operative functions in connection with pistons I are concerned, as if said cylinder were separable, that is, a two part cylinder; and the single cylinder provided with a slot, instead of two cylinders (one at each end of middle part a) is used simply to avoid the mechanical difficulties attending the mounting of two cylinders on the same axial line.

I claim:

1. A shell, oppositely placed pistons in said shell, said pistons positioned to obtain chambers in front thereof, a connection be-

- tween said pistons adapted to form a stem joining said pistons together in a determined relation to each other, a lever, means to move said lever, said lever associated with said stem to move said stem on the movement of said lever, said pistons and stem provided with passage ways which communicate with the chambers in front of said pistons, seats to said passage ways and valves adapted to co-act with said seats, in combination with means positioned between the pistons to alternately open and close said valves from and on to said seats upon a change of the direction of movement of said stem.
2. A shell, oppositely placed pistons in said shell, said pistons positioned to obtain chambers in said shell in front of said pistons, a stem joining said pistons together in said position, said stem provided with an aperture midway thereof and apertures adjacent to said pistons, and said pistons and stem provided with passage ways respectively communicating with said chambers, in combination with a lever, a fulcrum to said lever on said shell, said lever positioned so that one end thereof is in said midway aperture in said stem, valves positioned to close said passage ways when said valves are seated, means to yieldingly hold said valves seated, and means positioned between said pistons and comprising abutments extending through said apertures which are adjacent to the pistons to alternately unseat said valves upon a change of direction of movement of said pistons.
3. A shell provided with cylindrical ends, oppositely placed pistons in said cylindrical ends, a stem joined to said pistons to obtain chambers in front of said pistons and a chamber between them, a journal bearing to said shell between said pistons, said pistons and stem provided with passage ways communicating with said chambers in front of said pistons and with said chamber between said pistons, in combination with a lever mounted to rock in said journal bearing, said lever and said stem connected so that movement of said lever moves said stem, valves positioned close to said passage ways when seated and means to yieldingly hold said valves seated, and means positioned in the chamber between said pistons to alternately unseat said valves upon a change of direction of movement of said pistons.
4. Oppositely placed pistons, a stem joining said pistons together, a shell provided with chambers in which said pistons are longitudinally movable, said pistons and stem provided with passage ways communicating with the chambers on opposite sides of said pistons, valves to said passage ways, said valves adapted to close said passage ways when seated, in combination with means to move said pistons and means positioned be-
- tween said pistons to alternately unseat said valves upon a change of direction of movement of said pistons.
5. A casing provided with cylindrical portions, oppositely placed pistons in said cylindrical portions, a bearing on said casing, said pistons positioned to obtain chambers between said pistons and in front thereof, a stem spacing and joining said pistons, said pistons and stem provided with passage ways communicating with the chamber between the pistons and with the chambers in front of the pistons, and valves in said passage ways adapted to seat and close the same, in combination with a lever connected to said stem, and mounted so that said bearing is the fulcrum thereof, and means positioned in the chamber between the said pistons to alternately unseat said valves upon a change of direction of movement of said pistons.
6. A casing comprising a middle part and closed cylindrical end parts attached to said middle part, said end parts open to said middle part and said middle part provided with a journal bearing, means to attach said casing to a vehicle, pistons in said end parts, a stem spacing and joining said pistons, said pistons and stem provided with passage ways communicating with said end parts and with said middle part, and valves adapted to seat and close said passage ways, in combination with a shaft in said bearing, levers to said shaft, a connection between one of said levers and the body of said vehicle and between the other of said levers and said stem, and mechanism associated with said end parts adapted to be held stationary by friction and on the change of movement of said pistons to alternately force said valves from the seats thereof.
7. Oppositely placed pistons, a casing provided with chambers in which chambers said pistons are longitudinally movable, a stem spacing and joining said pistons to obtain a chamber between the pistons and chambers in front of said pistons, said stem provided with lateral apertures and said pistons provided with passage ways communicating with the chambers in front of said pistons and with said apertures, valves adapted to seat and close said passage ways, respectively, in combination with means to move said pistons, and means to unseat said valves on the change of direction of movement of said pistons, said unseating means comprising additional and two-part pistons, said parts connected by members extending through said lateral apertures and adapted to engage with the said valves, and springs adapted to force said parts against the walls of said chambers.
8. A casing comprising a middle part attachable to a vehicle and cylindrical part at-

tachable to said middle part, said cylindrical part closed at its ends, in combination with 5 pistons movable in said cylindrical part, a stem spacing and joining said pistons, said pistons provided with passage ways therethrough respectively communicating with the chambers in front of and between said pistons, valves seating to close said passage ways, additional pistons movably mounted 10 between said first named pistons and movable in said cylindrical part independently of the movement of said first named pistons, said additional pistons associated with said cylindrical part to be yieldingly held stationary on the change of direction of movement of said first named pistons during a determined travel thereof and to thereby alternately unseat said valves.

9. A cylinder provided with a slot through 20 the wall thereof midway of its ends, means to close said ends of said cylinder, a shell provided with a bearing, said cylinder adapted to be held in said shell with said slot contained in said shell, pistons movably 25 mounted in said cylinder, a stem spacing and joining said pistons, a lever fulcrumed in said bearing and extending through said slot to and connected with said stem, said shell

and lever attachable to the axle and body of a vehicle, respectively, said pistons respectively provided with passage ways from one side thereof to the other side, valves seating to close said passage ways, and means to move said valves to alternately open the passage way in one of said pistons and close the passage way in the other of said pistons on the change of direction of movement of said pistons.

10. A casing, pistons movable in said casing, said pistons provided with passage ways therethrough, means to space and join said pistons, ports to said passage ways, and means to move said pistons, in combination with valves adapted to co-act with said ports, and means positioned between said pistons to move said valves to alternately uncover said ports on the change of direction of movement of said pistons, said valve moving means in frictional association with said casing and arranged to open the rear port on 50 said change of movement.

CHARLES TURNER BROWN.
